ELECTRIC RAZOR

Filed Sept. 28, 1927

2 Sheets-Sheet 2

UNITED STATES PATENT OFFICE.

JARRETT C. HOLCOMB, OF SULPHUR SPRINGS, TEXAS, ASSIGNOR OF ONE-HALF TO
ROBERT F. CAMERON, OF DALLAS, TEXAS.

ELECTRIC RAZOR.

Application filed September 28, 1927. Serial No. 222,641.

This invention relates to cutlery and more particularly to a razor.

One object of the invention is to provide a razor having a handle including a blade-holding element and electrically energized means within the handle to impart vibratory movement to the blade holder longitudinally thereof and thereby cause the blade to vibrate longitudinally when in use 10 and very easily cut through the beard as the blade is moved across the face.

Another object of the invention is to provide a blade holder and vibrator consisting of a coil and a plunger slidably longitudinally through the coil and having one end portion extending from the handle and adapted to carry a blade, the blade being 15 removably engaged with the outer end of the plunger so that it may be disconnected 20 therefrom when not in use.

Another object of the invention is to yieldably support the plunger by resilient supporting means disposed within the handle and engaged with end portions of 25 the plunger projecting from the coil thereby permitting the plunger to be moved longitudinally but eliminating bearings and other parts which are liable to wear and prevent the plunger from remaining in its proper 30 position.

Another object of the invention is to form the blade holder and vibrating means as a combined solenoid and electro-magnet and thereby permit the plunger which carries 35 the blade to be very easily moved longitudinally when the coil is energized.

Another object of the invention is to permit the resilient supporting means to yieldably resist inward movement of the plunger 40 and the combined electro-magnet and solenoid to intermittently overcome the resilient supporting means and draw the plunger inwardly when the coil is energized.

Another object of the invention is to control the action of the resilient supporting means engaged with one end portion of the plunger and thereby regulate the amount of vibration imparted to the plunger and blade carried thereby.

Another object of the invention is to provide an improved switch for controlling passage of current to the coil.

The invention is illustrated in the accompanying drawings, wherein:

Figure 1 is a view showing the improved 55 razor in side elevation;

Fig. 2 is a longitudinal sectional view through the razor;

Fig. 3 is a transverse sectional view 60 through the handle taken on the line 3-3 of Fig. 2 and illustrating the switch mechanism;

Fig. 4 is a similar view taken on the line 4-4 of Fig. 2, illustrating the manner of 65 yieldably supporting one end portion of the plunger of the coil;

Fig. 5 is a transverse sectional view taken on the line 5-5 of Fig. 2, illustrating the 70 supporting means for the other end portion of the plunger;

Fig. 6 is a transverse sectional view taken on the line 6-6 of Fig. 2, showing the forward end of the handle in elevation;

Fig. 7 is a fragmentary sectional view 75 taken on the line 7-7 of Fig. 4, and

Fig. 8 is a fragmentary sectional view taken on the line 8-8 of Fig. 3.

The razor includes a handle, indicated in general by the numeral 1, and a blade 2 which is removably connected with a blade holder 3 projecting forwardly from the handle. Since the blade is removably secured, it can be released when it is necessary to strop or clean the blade and there will be no danger of the handle and the electrically energized apparatus therein becoming wet with resultant danger of a short circuit. The handle is in the form of a casing having a tubular body 4 formed of sheet metal perforated, as shown in Fig. 1, 80 and having caps 5 and 6 at its ends which are loosely mounted so that they may be turned for a purpose to be hereinafter set forth.

Within the casing is disposed a combined 85 solenoid and electro-magnet including a sleeve 7 having heads 8 and 9 secured adjacent its ends and between which wire is wound in a conventional manner, as shown at 10. A stationary core 11 is rigidly secured in one end portion of the sleeve 7 and in the other end portion of the sleeve is fitted a movable core 12 adapted to be drawn into the sleeve when current is passed 100 through the coiled wire 10 both by the action of the current passing through the wire after the manner in which a solenoid works 105 and also by the attraction of the core 11

which becomes magnetized while current is passing through the wire after the manner of an electro-magnet. It will thus be seen that the coil together with the stationary core and the movable core will have the combined action of a solenoid and an electro-magnet and the movable core will be caused to very easily move inwardly when the coil is energized. The reduced portion 13 of the movable core or plunger extends through the bore of the stationary core and projects rearwardly therefrom. The projected end portion of the plunger is threaded and carries securing nuts 14 between which 18 is disposed a resilient support 15 formed preferably of thin sheet brass. The resilient strip 15 extends radially from the plunger in opposite directions, as shown in Fig. 4, and at its ends carries side arms 16 which extend circumferentially of the casing and have their ends fitted upon posts 17 where they are firmly secured by nuts 18. The posts are carried by and project from the head 8 in diametrically opposed relation 25 to each other.

The portion of the plunger which projects forwardly from the coil carries a resilient support 19 which is rigidly secured thereto and is similar in its construction to the support 15 but preferably formed of spring steel. This support also extends radially from the plunger, as shown in Fig. 5, and at its ends is provided with side arms 20 fitted upon posts 21 which project from the head 9 and secured by nuts 22. Plates 23 fit loosely upon the plunger in close contacting engagement with opposite faces of the resilient strip 19 so that they may be turned about the plunger and at their ends 30 are formed with jaws 24 which engage opposite faces of the side arms 20. While the plates 23 may be turned about the plunger, they may not have movement longitudinally thereon. It will thus be seen that by turning 35 the plates to move their jaws along the arms 20 the distance between the jaws and the posts 21 may be controlled and the extent to which the arms are allowed to flex thereby controlled. Since the flexing of the resilient support may be regulated, the distance the plunger will move when the coil 40 is energized may be controlled and either a short or a long reciprocating movement imparted to the blade. In order to adjust 45 the plates and move their jaws toward and away from the posts, I have provided a link 25 which has one end secured to the cap 6 by a rivet 26 and its other end fitted upon a pin 27 carried by one of the plates. By 50 referring to Fig. 5, it will be readily seen that when the cap 6 is rotated, the plates will be turned about the core and their jaws slid along the arms of the resilient support. In order to retain the cap upon the casing 55 and permit it to be turned to adjust the

plates, I employ screws 28 which pass through arcuate slots 29 formed in the cap and have their inner ends screwed into threaded openings formed in brackets 30 carried by the posts 21. It will thus be seen that the cap 6 serves not only as means to close the forward end of the casing but also constitutes actuating means through the medium of which longitudinal vibration of the plunger and blade may be controlled. 75

The cap 5 which closes the rear end of the casing is formed with an enlarged central opening which fits about a circular boss 31 formed upon a disk 32 of insulating material. This disk has openings 33 formed therein across which extend contact plates 34 and 35 having openings to receive posts 36 carried by blocks 37 which are secured to the head 8 of the coil by screws 38, as shown in Fig. 7. The terminals 39 of the wire 85 from which the coil 10 is formed fit upon the posts 36 where they are secured by nuts 40 and sleeves 41 of conductive material are placed upon the posts against the nuts 40 and engage the contacts 34 and 35 when 90 the posts are passed through the openings in the contacts and the securing nuts 42 fitted upon their ends and tightened. The terminal posts 43 and 44 which are to be fitted into a socket carried by a conductor 95 wire are embedded in the boss 31 which is also formed with threaded sockets to receive screws 45 by means of which a retainer ring 46 for the cap 5 and the terminal 43 is connected with the contact plate 34 by 100 a wire 47 embedded in the disk. A similar wire 48 leads from the terminal 44 and is anchored to a plate 49.

Since the disk is formed of insulating material, the plate 49 and contact plate 35 will 105 be insulated from each other and a circuit cannot be established through the coil until connection is provided between the two. In order to do so, there has been provided a switch arm 50 which is pivotally mounted by 110 means of a screw 51 which also passes through a plate 52 and is screwed into the plate or block 49, as shown in Figs. 2 and 3. An abutment 53 extends from the hub portion of the switch arm between lugs 54 and 115 55 carried by the plate 52 so that when the plate is turned about the screw the lugs will engage the abutment and swing the switch arm about the screw from the closed position shown in Fig. 3 in which it engages the under 120 face of the tongue 56 extending from the plate 35 to an open position in which the free end of the switch arm fits beneath the bracket 57. Pins 58 and 59 are provided to engage the switch arm and limit its swinging 125 movement. The spring 60 which yieldably retains the actuating plate 52 in a set position is formed of resilient wire bent to provide a center coil having arms 61 and 62 extending from it, one of which is anchored to 130

the screw 63 and the other engaged in an opening formed in an ear 64 projecting from the hub portion of the actuating plate. Arms 65 and 66 extend from the opposite side or end portion of the actuating plate and project across an arcuate slot 67 formed in the disk 32 and the cap 5 carries a pin 68 which projects through the slot 67 between the arms so that when the cap is turned about the boss 31 the pin by engaging one of the arms may move the actuating plate against the action of the spring and by contact with the abument 53 swing the switch arm to either an open or a closed position. It will thus be seen that the cap 5 constitutes means to open and close the switch as well as serving as a closure for the rear end of the handle casing.

The forward end portion 69 of the plunger which projects outwardly from the handle is flattened, as shown in Fig. 6, and is formed with a socket 70 which opens through its forward end and is adapted to receive the shank 71 of the blade 2. A spring strip 72 extends longitudinally in the socket and is engaged by a set screw 73 which passes through a threaded opening formed in the boss 74 of the plunger so that when the set screw is turned inwardly pressure will be applied to the spring strip in order to force the strip into tight gripping engagement with the shank of the blade. Therefore, the blade will be securely but releasably retained in engagement with the outer end of the plunger or blade carrier. By unscrewing the set screw, the blade will be released and may be easily withdrawn so that it may be stropped or cleaned and put away after being used.

When the razor is in use, the blade is secured in the socket 70 and the terminal posts 43 and 44 engaged in the socket of a conductor wire. By rotating the cap 5, the switch may be closed and current will pass through the coil to energize it. This razor is intended to be energized by alternating current and as the cycles of the current take place very rapidly the plunger will be rapidly reciprocated longitudinally and the razor blade will be vibrated longitudinally at a rapid rate of speed but the movement will not be sufficient to cut the face of a person handling the razor. By turning the cap 6, the longitudinal movement of the plunger and blade can be controlled and the blade allowed to reciprocate longitudinally to cause it to very easily pass through the beard with a slicing motion without the longitudinal movement causing the razor to cut the face. If it is found desirable to do so, the switch may be opened and the razor used without vibrating movement of the blade taking place.

Having thus described the invention, I claim:

1. In a device of the character described, a handle comprising a casing, a solenoid in said casing including a coil and a plunger extending through the coil and projecting from its ends, one end portion of the plunger 70 extending out of the handle and constituting a blade holder, and a resilient strip in the casing extending transversely thereof and secured at its ends and having its intermediate portion engaged with said plunger 75 to yieldably support the plunger and permit the same to be intermittently drawn inwardly when the coil of the solenoid is energized.

2. In a device of the character described, a solenoid including a coil and a plunger extending through the coil axially thereof with its end portions projecting from the coil and one end portion adapted to carry a blade, resilient supporting means for said plunger engaged with the portions thereof 85 projecting from the coil to yieldably support the plunger and permit the same to be intermittently moved longitudinally when the coil is energized, and means engaged with the resilient supporting means at one 90 end of the plunger to control the amplitude of movement of the plunger.

3. In a device of the character described, a solenoid including a coil and a plunger extending axially through the coil and having an end portion projecting therefrom and adapted to carry a blade, resilient supporting means for said plunger yieldably supporting the same and permitting the plunger to be intermittently moved longitudinally 100 when the coil is energized, and means engaged with the resilient supporting means to control movement of the plunger.

4. In a device of the character described, a combined solenoid and electro-magnet including a coil having heads at its ends, a stationary core for said coil having an axially extending passage, and a movable core for the coil slidable longitudinally therein and having a portion extending through the passage of the stationary core, the movable core having its end portions projecting from the coil and one end portion being adapted to carry a blade, and resilient supporting means carried by the heads of the coil and secured to the end portions of the movable core to yieldably support the same and permit longitudinal movement thereof when the coil is energized.

5. In a device of the character described, a handle including a casing, caps for the ends of said casing, a coil in said casing rigidly secured therein and having heads at its ends spaced from said caps, a plunger slidable axially through the coil and having its end projecting therefrom and one end portion extending through the adjacent cap and adapted to carry a blade, and resilient supporting means carried by the heads of said coil and engaged with the end portions 120

of said plunger to yieldably support the plunger and permit the same to be intermittently moved longitudinally when the coil is energized.

- 5 6. In a device of the character described, a handle including a casing, caps for the ends of said casing, a coil in said casing rigidly secured therein and having heads at its ends spaced from said caps, a plunger 10 slideable axially through the coil and having its end projecting therefrom and one end portion extending through the adjacent cap and adapted to carry a blade, and resilient supporting means mounted between the heads 15 of the coil and caps of the casing and engaged with the end portions of said plunger to yieldably support the plunger and permit the same to be moved longitudinally when the coil is energized.
- 20 7. In a device of the character described, a handle including a casing, caps for the ends of said casing, a coil in said casing rigidly secured therein and having heads at its ends spaced from said caps, a plunger 25 slideable axially through the coil and having its end projecting therefrom and one end portion extending through the adjacent cap and adapted to carry a blade, resilient supporting strips engaged with the end portions 30 of said plunger between the coil and ends of said casing, control means for one resilient strip movably mounted and slidably engaged therewith, and means carried by the adjacent cap to impart movement to said 35 control means.

8. In a device of the character described, a handle including a casing, caps for the ends of said casing, a coil in said casing rigidly secured therein and having heads at its ends spaced from said caps, a plunger 40 slideable axially through the coil and having its end projecting therefrom and one end portion extending through the adjacent cap and adapted to carry a blade, posts 45 extending from the heads of said coil at opposite sides of said plunger, and spring strips secured to the end portions of the plunger and projecting radially therefrom and provided with side arms extending circumferentially of the casing and secured to said 50 posts to yieldably support the plunger and permit longitudinal movement thereof when the coil is energized.

9. In a device of the character described, 55 a handle including a casing, caps for the ends of said casing, a coil in said casing rigidly secured therein and having heads at its ends spaced from said caps, a plunger 60 slideable axially through the coil and having its end projecting therefrom and one end portion extending through the adjacent cap and adapted to carry a blade, posts extending from the heads of said coil at opposite sides of said plunger, spring strips engaged 65 with the plunger and extending radially

therefrom within the casing and having side arms extending circumferentially of the casing and secured to said posts to yieldably support the plunger, control means for one spring strip slidably engaged with the arms 70 thereof, and means to adjust the control means.

10. In a device of the character described, a handle including a casing, caps for the ends of said casing, a coil in said casing 75 rigidly secured therein and having heads at its ends spaced from said caps, a plunger slideable axially through the coil and having its end projecting therefrom and one end portion extending through the adjacent cap 80 and adapted to carry a blade, posts extending from the heads of said coil at opposite sides of said plunger, spring strips engaged with the plunger and extending radially 85 therefrom within the casing and having side arms extending circumferentially of the casing and secured to said posts to yieldably support the plunger, control means loosely 90 mounted upon an end portion of said plunger and having arms slidably engaged with the arms of the adjacent spring strip for movement longitudinally thereof when the control means is moved about the plunger, the adjacent cap being turnable, and means connecting the said adjacent cap with said 95 control means whereby the cap when turned may impart movement to the control means.

11. In a device of the character described, a handle including a casing, caps for the ends of said casing, a coil in said casing 100 rigidly secured therein and having heads at its ends spaced from said caps, a plunger slideable axially through the coil and having its end projecting therefrom and one end portion extending through the adjacent cap 105 and adapted to carry a blade, resilient supporting strips engaged with the end portions of said plunger between the coil and ends of said casing to yieldably support the plunger and permit longitudinal movement thereof 110 when the coil is energized, a switch for said coil in one end portion of said casing, the adjacent cap being turnable, and means extending from the said adjacent cap to open and close the switch when the cap is turned. 115

12. In a device of the character described, a handle including a casing, caps for the ends of said casing, a coil in said casing 120 rigidly secured therein and having heads at its ends spaced from said caps, a plunger slideable axially through the coil and having its end projecting therefrom and one end portion extending through the adjacent cap and adapted to carry a blade, resilient supporting strips engaged with the end portions of said plunger between the coil and ends of said casing to yieldably support the plunger and permit longitudinal movement thereof 125 when the coil is energized, posts extending from one head and having ends of 130

the coil anchored thereto, an insulating disk carried by said posts and turnably mounting the adjacent cap of said casing, conductor terminals carried by said disk, contacts carried by said disk and engaging said posts, one contact being connected with a terminal, a switch arm connected with the other terminal, and means extending from the turnable cap to move the switch into and out of engagement with the last-mentioned contact when the cap is turned.

13. In a device of the character described, a handle including a casing, caps for the ends of said casing, a coil in said casing rigidly secured therein and having heads at its ends spaced from said caps, a plunger slidable axially through the coil and having its end projecting therefrom and one end portion extending through the adjacent cap and adapted to carry a blade, resilient supporting strips engaged with the end portions of said plunger between the coil and ends of said casing to yieldably support the plunger and permit longitudinal movement thereof when the coil is energized, posts extending from one head and having ends of the coil

anchored thereto, an insulating disk carried by said posts and turnably mounting the adjacent cap of said casing, conductor terminals carried by said disk, contacts carried by said disk and engaging said posts, one contact being connected with a terminal, a switch arm pivotally mounted at one end and connected with the other terminal, said arm extending radially across the inner face of the disk and movable into and out of position to engage the other contact, an abutment carried by the pivotal end of said switch arm, an actuating plate pivoted concentric to the switch arm and having lugs to engage said abutment disposed at opposite sides thereof and arms extending across an arcuate slot in the disk, a spring yieldably resisting movement of said actuating plate, and a pin extending from said cap through the slot in the disk between the arms of the actuating plate to engage the same and impart movement to the actuating plate to adjust the switch arm when the cap is turned.

In testimony whereof I affix my signature.

JARRETT C. HOLCOMB. [L. S.]
